ELECTRIC SWITCH

Emil Lange, Berlin, Germany

Application February 10, 1932, Serial No. 592,093
In Germany January 12, 1930

6 Claims. (Cl. 200—148)

This invention relates to improvements in electric switches, more particularly to switches the contact members of which are arranged within a pressure chamber or pressure retaining vessel. 5 In switches of this type, when the arc is formed between the separating contact members, an increase in pressure occurs within said vessel. This increase in pressure causes a stream of liquid or gases to flow between the separating contact members extinguishing the arc and preventing the contact members to be damaged.

One object of the invention is to extinguish the arc without any quenching liquid. The use of oil is open to the objection that vapors are produced which, when ignited, cause the explosion of the switch. On the other hand, switches provided with an electrolyte e. g. water as a quenching liquid are open to the disadvantage of the formation of oxyhydrogen which on being ignited causes also an explosion of the switch.

Another object of the invention is to provide means for strongly cooling the separating contact members.

Another object of the invention is to provide 25 means for preventing a blast of gases to be directed into the path of the arc before a predetermined increase in pressure occurs within the pressure retaining vessel.

Other objects of the invention will appear from 30 the following description in connection with the accompanying drawing in which several embodiments of the invention are illustrated diagrammatically by way of example.

Fig. 1 shows a switch with a pressure chamber 35 or pressure retaining vessel surrounding the cooled point of break.

Fig. 2 is a switch similar to that shown in Fig. 1, but with two points of break.

Fig. 3 shows a switch with a pressure chamber 40 surrounding the break point and connected to a pressure gas bottle through a valve.

Fig. 4 shows a switch similar to that illustrated in Fig. 3.

In a compartment 85 (Fig. 1), which may be 45 of rectangular or circular shape, and which constitutes the pressure or arc chamber, contacts 21 and 22 are arranged. The contact bolt 21 is movable and actuated from outside by an ordinary driving mechanism (not shown) for making and 50 breaking the contact with the contact member 22. The wall 23 of the pressure chamber 85 is made of an electric and heat insulating material, such as porcelain. The stationary contact 22 is hollow and the hole of this contact forms the 55 sole gas outlet of the pressure chamber 85, thus

compelling the compressed gas to blow out through the arcing spot. The gas outlet proper of the switch lies immediately behind the perforated or hollow contact 22. This outlet is closed by a weighted or spring-controlled closing element or valve 24, which opens towards the outer room under the effect of an inner over pressure of a predetermined value and closes when the pressure in the compartment 85 drops. For increasing the heat insulation of the compartment 85, a 10 casing 25 is provided, and the space 26 between the walls of said casing and the walls 23 of the chamber 85 is filled with cork or similar heat-insulating material. In the compartment 85, 15 cooling means for the contact members 21 and 22 are further provided for example, a container 29, filled with carbon dioxide, which gives off cold while evaporating to the gas contained in chamber 85. Closing means 30 are disposed in an opening 31 in the walls 23 and 25 to enable the 20 refilling of the container 29. This opening 31 also ensures an easy control of the switch contacts.

The switch operates in the following manner:

An arc forms in the compartment 85 when the contacts 21 and 22 are separated. This arc has a high temperature. There is a considerable rise in pressure in the air or gas in the chamber produced by the heat of the arc. The temperature 30 of the gaseous medium filling the compartment 85 is at the same time strongly diminished by the carbon dioxide evaporating in the container 29. The relatively great temperature difference between the arc and the surrounding atmosphere 35 thus obtained and the relatively great pressure rise thereby created cause a strong outflow of carbon dioxide through the tubular contact 22 and through the outlet of the valve 24, which is the more increased, the more the gas included in 40 chamber 85 is cooled due to the evaporation of carbon dioxide. Owing to the sudden increase of pressure in the compartment 85, the valve 24 becomes opened so that the gas, under high pressure, 45 quickly escapes. Thus, the arc between the contact members 21 and 22 is quickly extinguished. The compartment 85 remains, after the switching-off operation, i. e., after the extinguishing of the arc, filled with carbon-dioxide gas at a certain pressure determined by the spring of the valve 24. 50 This pressure is preferably considerably above atmospheric, as it is then necessary to impart to the gaseous medium in the chamber a relatively small quantity of heat by the arc in order to get the rise in pressure wanted for expelling the gases and extinguishing the arc rapidly. This is particu-

larly true for small arcs, i. e., when the power to be switched off is small. Apparently, the extinguishing of an arc by evaporating carbon dioxide is much more effective than by air, but the invention is applicable to use with strongly cooled air also.

A switch with two make-and-break contacts, main and auxiliary, is illustrated in Fig. 2.

A movable traverse 34, actuated by a driving rod 35, is situated in the compartment 32 and provided with two contact members 33 and 33' adapted to co-operate with contact members 36 and 37. The contact member 37 is hollow, permitting the outflow of compressed gas and the contact member 36 is solid. The main contact members 33, 37 are connected to the auxiliary contact members 33' and 36. The contact members 36 and 37 are fixed in the inner wall 38 of a casing surrounding the pressure chamber 32, the hollow walls of which casing are preferably filled with heat and electric insulating material. Cooling means 39, similar to the cooling means 29 of Fig. 1, are located in the compartment 32, accessible through an aperture 41 that may be closed by a closing means 40. These cooling means may consist, for instance, of carbon dioxide snow, thus developing at the same time gas and cold. The hollow formed in the contact member 37 is closed by a valve 42 (that may be held closed in the same manner as the valve 24), as long as there takes place no interruption of the contact members being under voltage. The pressure compartment 32 is on its outside provided with a wall 43, that forms a pressure-proof casing for the hollow rooms filled with thermo-insulating material.

The valve 42 of Fig. 2, like the valve 24 of Fig. 1, is adjusted to allow the gases produced in the compartments 35 and 32, respectively, to flow out therefrom only after a certain pressure is reached. The arc is extinguished in the same manner as before described, the auxiliary contact members 33' and 36 connected in series to and co-operating with the main contact members 33 and 37 as is customary in devices of this nature. The arc produced by the auxiliary contact members 33' and 36 will produce a considerable increase in pressure in the chamber 32. This gas pressure will naturally become increased upon the opening of the main contact members 33 and 37, with the result that the gases will be forced out of the chamber 32, through the valve 42, with a corresponding high speed and despatch.

Instead of maintaining a reserve of carbon dioxide snow in the pressure chamber 32, which must be replenished from time to time, liquid carbon dioxide may be supplied in such a manner to the pressure chamber, that it is converted into carbon dioxide snow on entering the pressure chamber.

Fig. 3 illustrates a switch of this kind with a pressure chamber surrounding the point of break 45, 46 and connected by a valve to a container containing liquid carbon dioxide.

In the pressure chamber 44, the stationary contact member 45—forming a hollow contact—and the movable contact 46 forming a pin, are arranged. An admission nozzle 47 is provided, in the lower portion of the pressure chamber 44, for introducing the compressed gas necessary for continuously maintaining the gas pressure in the chamber. The pressure chamber is kept closed by a spring-closing valve 48 or the like. The pressure chamber communicates with a gas cylinder 50 filled with liquid gas, for instance, carbon dioxide, through a pipe conduit 49. A reducing

valve 51 serves for regulating the pressure to be maintained continuously, when the contact members are closed, and the force of the permanent gas flow dependent on said pressure.

The switch shown in Fig. 3 operates in the following manner:

Pressure is produced and maintained in the pressure chamber 44 by the gas entering from the gas cylinder 50. The force of this pressure in the pressure chamber 44 is maintained suitably reduced at a substantially constant or uniform value by means of the reducing valve 51 to prevent opening of the valve 48.

The arc produces an increase of pressure in the pressure chamber 44 during the separation of the contact members 45 and 46. Owing to this increase in pressure, the valve 48 becomes opened to permit the gas produced to flow intensely through the hollow contact member 45, thus to extinguish the arc.

The special advantage of this arrangement lies in the continuously existing uniform pressure in the pressure chamber, as long as no switching-off takes place, making it unnecessary to adjust the valve through which the gases are forced to extinguish the arc.

As shown in Fig. 4, a reserve of carbon dioxide or other cold-producer 100 is always present in the pressure chamber 44.

For this purpose, the pressure vessel 50 filled with liquid carbon dioxide is so arranged, as by turning it upside down, as compared with Fig. 3, that liquid carbon dioxide fills the connecting conduit 49, and, on leaving a nozzle 47 projecting into the pressure chamber, can evaporate and solidify to form carbon dioxide snow 100. The nozzle 47 is preferably made adjustable in order that the quantity of carbon dioxide snow to be formed may be regulated. A reducing valve inserted in the conduit 49 is permanently open.

The above described invention has important advantages over the high-efficiency switches of the prior art. Owing to the strong pre-cooling effect of the carbon-dioxide gas surrounding the switch contact members, a considerably greater increase of pressure will be produced by the arc in the pressure chamber, and consequently a more rapid extinction of the arc will take place than occurs in other switches.

What is claimed is:

1. An electric switch of the type in which the contact is made within a gaseous medium having, in combination, a pressure chamber provided with an outlet, a stationary contact member disposed in the path of the gas flowing into the outlet, a movable contact member within said pressure chamber for co-operating with the stationary contact member, a valve in the pressure chamber for normally closing the outlet, and means operable independently of the movement of the movable contact member for automatically opening the valve when the pressure in the pressure chamber rises to a predetermined value.

2. An electric switch of the type in which the contact is made within a gaseous medium having, in combination, a pressure chamber provided with an outlet, a hollow stationary contact member disposed near the outlet, a movable contact member within said pressure chamber for co-operating with the stationary contact member, a valve in the pressure chamber for normally closing the outlet, and means operable independently of the movement of the movable contact member for automatically opening the valve when the pres-

sure in the pressure chamber rises to a predetermined value.

3. An electric switch of the type in which the contact is made within a gaseous medium having, 5 in combination, a pressure chamber provided with an outlet, a stationary contact member disposed near the outlet, a movable contact member within said pressure chamber for co-operating with the stationary contact member, a valve in the 10 pressure chamber for normally closing the outlet, means operable independently of the movement of the movable contact member for automatically opening the valve when the pressure in the pressure chamber rises to a predetermined 15 value, and a volatile, cold-generating medium in the pressure chamber for cooling the gaseous medium therein.

4. An electric switch of the type in which the contact is made within a gaseous medium having, 20 in combination, a pressure chamber provided with an outlet, a hollow stationary contact member disposed near the outlet, a movable contact member within said pressure chamber for co-operating with the stationary contact member, a valve in the 25 pressure chamber for normally closing the outlet, means operable independently of the movement of the movable contact member for automatically opening the valve when the pressure in the pressure chamber rises to a predetermined value, 30 and a volatile, cold-generating medium in the pressure chamber for cooling the gaseous medium therein.

5. An electric switch of the type in which the contact is made within a gaseous medium, having 35 in combination, a pressure chamber provided with an outlet, a stationary contact member disposed near the outlet, a movable contact member with-

in said pressure chamber for co-operating with the stationary contact member, a valve in the pressure chamber for normally closing the outlet, means operable independently of the movement of the movable contact member for automatically 5 opening the valve when the pressure in the pressure chamber rises to a predetermined value, a vessel for containing gas under pressure, a conduit connecting the vessel with the pressure chamber, and a reducing valve in the conduit, the 10 reducing valve being adjustable to maintain the gas pressure permanently present in the pressure chamber below the said predetermined value.

6. An electric switch of the type in which the contact is made within a gaseous medium having, 15 in combination, a pressure chamber provided with an outlet, a stationary contact member disposed near the outlet, a movable contact member within said pressure chamber for co-operating with the stationary contact member, a valve in the 20 pressure chamber for normally closing the outlet, means operable independently of the movement of the movable contact member for automatically opening the valve when the pressure in the pressure chamber rises to a predetermined value, 25 a vessel for containing gas under pressure, a conduit connecting the vessel with the pressure chamber, a reducing valve in the conduit, the reducing valve being adjustable to maintain the gas pressure permanently present in the pressure 30 chamber below the said predetermined value, the vessel being disposed top-side down above the conduit, whereby liquid carbon dioxide contained therein flows into the conduit, and a nozzle in the pressure chamber connected with the conduit. 35
